JOHN TYLER GREENE, OF TOLEDO, OHIO, ASSIGNOR TO THE NATIONAL ELECTRIC SPECIALTY COMPANY, OF TOLEDO, OHIO, A CORPORATION OF OHIO.

VACUUM LIGHTNING-ARRESTER.

1,191,690.

Specification of Letters Patent.

Patented July 18, 1916.

Application filed December 16, 1912. Serial No. 737,017.

To all whom it may concern:

Be it known that I, JOHN T. GREENE, a citizen of the United States, residing at Toledo, in the county of Lucas and State 5 of Ohio, have invented certain new and useful Improvements in Vacuum Lightning-Arresters, of which the following is a specification.

My invention relates to lightning arresters of the vacuum type, and the invention has for a primary object to provide a convenient, durable and inexpensive mounting for the electrodes of a vacuum lightning arrester which will accurately and permanently 10 position said electrodes within the evacuated vessel and at proper distances, one from another, so that the spark gap or gaps will not be destroyed or altered by rough handling in shipment, or vibration 15 and the like, when the devices are used.

A further object is to provide a mounting of the sort above indicated, which will protect the seals of the leading-in wires from the effects of the discharge across the spark 20 gap or gaps.

The invention is illustrated in the accompanying drawings, wherein Figure 1 is a longitudinal sectional view showing a preferred embodiment of the invention; Fig. 30 2, a sectional plan taken on line 2-2 of Fig. 1; Fig. 3, a view, in perspective, of the non-conducting refractory element in which the electrodes are mounted, and Figs. 4 and 5, views, in perspective, of the electrodes.

Like characters of reference designate like parts in the several figures of the drawing.

Referring to the drawing, 10 designates a 40 base of refractory material, such as porcelain, upon which is mounted, in any suitable manner, an evacuated, or partially evacuated, vessel 11 preferably made of glass. The vessel is formed preferably with 45 an inwardly projecting glass stem 12 through which the leading-in wires are sealed. The arrester shown in the drawing is designed for a metallic circuit and hence there are three electrodes, two line electrodes, and a grounded electrode. 13 designates the grounded electrode, and 14, 14 the line electrodes. These electrodes are arranged in an element made preferably integrally, of some non-conducting, highly refractory material such as porcelain, which

is so formed and constructed as to engage the electrodes at both ends so as to prevent all possibility of displacement. The element, a detail of which is shown in Fig. 3, consists of a base 15 to which the electrodes 60 are attached by suitable securing devices, and a yoke 16 extending around and engaging the upper or free ends of said electrodes. The electrodes consist preferably of carbon blocks and, as a matter of convenience, the grounded electrode 13 (Fig. 4) is formed with lugs or feet 17 which are perforated for screws 18 by means of which the electrode is secured to the base 15. Each line electrode 14 (Fig. 5) is also preferably 65 formed with a projection or foot 19 perforated for an attaching screw 20. The transverse member of the yoke 16 is formed with a groove 21 into which the upper end of the grounded electrode fits, and with 70 similar grooves 22 for the line electrodes 14. The base 15 is preferably, though not necessarily, formed with projections 23, 23 intervening between the central electrode 13 and the electrodes 14 on the other side thereof. The grounded leading-in wire 24 is secured to the screw 18 and the leading-in wires 25, 25 for the line electrodes are similarly secured to the ends of the screws 20. The mounting structure 15, 16, may thus 75 be supported on the leading-in wires but preferably, in order to insure a firm and durable support for the same, I fill in the space around the ends of the leading-in wires and between the base member 15 and the stem 12 with a body 26 of asbestos cement, or other similar material, which, when it hardens, will give an additional support to the porcelain member 15, 16 and 80 the electrodes.

In lightning arresters of the vacuum type in which electrodes consisting of blocks of carbon, or other similar material, are arranged within an evacuated glass vessel through the walls of which the leading-in 85 wires are sealed, considerable difficulty has been experienced in obtaining a cheap and convenient means for mounting the electrodes which will firmly and reliably hold 90 said electrodes in the desired position as 100 against the rough handling which the arresters may receive in shipment and the vibration to which they may be subjected when 105 in use, as, for example, when used in railroad signaling work. My present invention pro- 110

22

vides means for mounting the electrodes which meets all these requirements. The electrodes are accurately and very firmly positioned by employment of the base member 15 with its yoke 16. Each end of each electrode is positively held in fixed position. The manufacture of the device is simple and inexpensive. The electrodes are slipped into the porcelain member 15, 16 and the screws 18, 20, driven through perforations previously formed in the base. The cement 26, besides holding the mounting element in position, gives an anchorage for the ends of the screws. It will be observed, furthermore, that as the base 15 intervenes between the seals of the leading-in wires and the electrodes the former are protected as against direct contact of the arcs across the spark gaps.

20 I claim.

1. A lightning arrester comprising an evacuated vessel provided with an inwardly projecting stem, leading-in wires sealed through said stem, a base member within said vessel, a plurality of carbon blocks to serve the function of electrodes, each formed with a perforated foot, attaching devices

extending through the perforations in said feet, and through said base member, with the extremities of which said leading-in wires 30 are connected, a body of plastic, non-conducting material between said stem and said base, a yoke, rigid with the base, which extends around and engages the outer ends of the carbon blocks so as to hold the same in 35 spaced relation.

2. A lightning arrester comprising an evacuated glass vessel formed with an in-turned stem, leading-in wires sealed through said stem, a base arranged above and transversely to the stem, having a yoke member thereon, both of nonconducting, refractory material, electrodes in parallel arrangement between and secured to said base and yoke and electrically connected with said leading-in wires respectively through the base, and a body of plastic, nonconducting material uniting the base to the stem and inclosing the upper ends of the leading in wires. 40 45
